1

This invention relates to electrical appliances for producing oscillations or vibrations for laundry purposes.

It has already been proposed to clean material to be laundered or washed, especially underwear, by rapidly vibrating or oscillating the washing water, in which the material to be laundered is immersed, by means of a membrane or diaphragm which is immersed or plunged into the water, with the object of releasing and washing away particles of dirt or other foreign matter adhering to the material being laundered. In a known washing device of this kind, the diaphragm is caused to vibrate rapidly by means of a small electric motor through a rod or bar to which the diaphragm is fitted. The disadvantages of this device consist in the fact that revolving parts requiring the attention of an operator and subject to wear and tear, are provided for translating a rotary movement into the required oscillating or vibrating movement.

It is also known to use ultra sound or supersonic waves for laundry purposes. The production of such waves, however, requires devices which are too cumbersome and expensive for use in small laundry installations for domestic use.

According to the present invention, and in order to avoid the disadvantages of the said known devices, an electro-magnetic driving means is employed for exciting a vibrating or oscillating body, the vibrations or oscillations of which are transmitted to the washing liquid.

The invention is further described with reference to the accompanying drawings which illustrate by way of example eight embodiments of the invention, suitable for alternating current, and in which:

Fig. 1 is a longitudinal section of the first embodiment incorporating a single electro-magnet and a single diaphragm.

Fig. 2 is a longitudinal section of a second embodiment incorporating two diaphragms actuated by a single electro-magnet.

Fig. 3 is a third example having two electro-magnets and two diaphragms, also in longitudinal section.

Fig. 4 is a further longitudinal section illustrating a fourth embodiment provided with a harmonic wave exciter in the form of an oscillating or vibrating beam or a corrugated circular disc.

Fig. 5 is a modification of the form shown in Fig. 4.

Fig. 6 is a sectional diagram showing an appliance according to this invention fitted in a laundry container, such as a boiler.

2

Fig. 7 is a fifth embodiment partly in longitudinal section of an appliance having a device adapted to compensate or balance the pressure differences in the interior of the appliance.

Fig. 8 is a longitudinal section through a part of the appliance shown in Fig. 7.

Fig. 9 is a sixth embodiment in longitudinal section, and

Fig. 10 is a fragmentary section showing a modification of this embodiment.

Fig. 11 is a longitudinal section of a seventh embodiment.

Fig. 12 is an eighth embodiment, also in longitudinal section.

In the appliance shown in Fig. 1, 10 designates a metal diaphragm in the form of a circular disc. In the centre of the disc is secured a bolt 11, with which a laminated iron body is firmly connected to constitute the armature 12 of an electro-magnet 13. A core 14 of the magnet with a coil 15, is secured to a casing 16 of the appliance. The diaphragm 10 is clamped between the edge of the casing 16 and a protective screen or lattice 17. The diaphragm thus tightly seals the casing around its periphery. The bolt 11 is carried at the end remote from the diaphragm in a plate spring 18 clamped to the base of the casing. A conduit or tube 19 is fitted to the casing and is co-axial with bolt 11 and so with the magnet. Said tube 19 serves as the carrier of the appliance and also for the passage of the electricity supply flex to the coil of the magnet.

When the appliance is connected with the electricity supply mains and set in operation, the electro-magnet periodically draws and releases its armature 12 in the rhythm or frequency of the alternating current to and from the core 14. Such reciprocating movement of the armature is transmitted to the diaphragm 10 and a vibration or oscillation corresponding to twice the mains frequency is consequently imparted to the diaphragm. The full vibratory or oscillatory movement which the diaphragm 10 tends to cover when the armature 12 is actuated, is, however,

not entirely utilised or exploited, the movement of the armature and so the diaphragm in a direction towards the magneto core being in fact, abruptly interrupted due to the armature 12 impinging upon the magneto core 14 which thus constitutes a stop. This impinging action causes the diaphragm to be jarred, i. e., the shape of the vibration curve of the diaphragm is influenced in such a way that peak or harmonic vibrations of very high frequency having very sharp rise and

fall are superimposed upon the basic vibration of the diaphragm.

The method of operation of the instrument or appliance when immersed in water is such that the molecules of the liquid entering the casing 16 via the screen or lattice 17 and surrounding the diaphragm are accelerated by the vibrations of the diaphragm. The greatly accelerated water particles are particularly suitable for and capable of removing particles of dirt or other foreign matter, which have already been loosened by the washing powder or other cleaning medium, from the fibre of the clothes or other material being laundered.

In the example shown in Fig. 2, two coaxially disposed diaphragms 25 and 26 are spaced apart and clamped or tensioned at opposite sides of a ring 27 together with respective screens or protective lattices 28 and 29. Both diaphragms are firmly connected with the excitation means so that the magneto core 14 is firmly connected with the diaphragm 25 and the armature 12 of the electro-magnet is firmly connected with the diaphragm 26. The carrier tube 19 is inserted into an aperture 30 in the ring 27 and is secured therein.

The example in Fig. 3 differs from that of Fig. 2 in that two diaphragms 31 and 32 are connected with respective armatures 33, 34 of two electro-magnets of which the respective cores 35 and 36 are secured on a plate or intermediate partition 38 firmly connected with and directing the annular casing 37 of the appliance.

In the example shown in Fig. 4, an additional vibratory body 40 is disposed on a bolt 39 which is secured to the diaphragm 10 and carries the armature 12. This additional vibratory body has its own frequency of vibrations, which is substantially above that of the diaphragm 10. The vibratory body 40 suspended in the middle of the diaphragm is in the form of a beam which tapers towards its ends. It may also, however, be constructed as a circular disc, which, as shown in Fig. 5, is provided with annular corrugations. Such additional vibrating or oscillating bodies are particularly suitable for superimposing heavy upper or harmonic vibrations upon the basic vibrations of the vibration system on the impinging of said vibration system.

The appliance is very simple to use and may be operated as follows. After the hot, or preferably, boiling water, to which is added the usual washing agents, and the laundry have been placed in the boiler 55 (Fig. 6) and the appliance has been suspended in the boiler so that its entire casing is submerged below the water level, the electric alternating current is switched on to cause the appliance to operate. For adjusting the depth to which the appliance is immersed, means such as an adjustable bearing ring 56 may be fitted to the carrier pipe 19 and which ring also serves to cover the aperture 57 in the lid 53 of the wash boiler, a fixing or clamp screw being carried by the ring to secure same in position. The appliance is preferably connected with the main supply through an electrical transformer which reduces the potential to a value which is not dangerous for contact with the body. An interrupter device of any suitable type may be built into the appliance and a condenser may also be provided if necessary so that the appliance may also be used on a direct current supply.

The vibrator or oscillation producer shown in Fig. 7 consists of a metal diaphragm 10 in the form of a circular disc which is clamped at its

outer edge to the casing 16 and connected hermetically with the casing by means of a packing ring 120. The laminated armature 12 of the electro-magnet 13 is fixed by means of the bolt 11 to the diaphragm in the centre thereof.

An aperture 160 for bolt 11 is hermetically sealed by a packing disc 170. The core 14 of the electro-magnet with the excitation coil 15 is secured to a strut or bridge 20 fixed to the base of casing 16.

The tube or pipe 19 is inserted into the base of the casing and is preferably securely welded thereto. A non-return valve 220 is provided at the free end of the pipe in order to prevent the admission of air from the atmosphere to the internal chamber or space of casing 16. The valve, which is shown in detail in Fig. 8, has a valve disc 230 formed with a conical bearing surface 240 which normally rests upon a correspondingly shaped seating surface formed at the end of pipe 19 and is pressed against this surface by a spring 250 which abuts against a cap nut 260 screwed on to a threaded collar fixed to this end of the pipe, the cap nut being provided with an aperture 270 for the passage of air. This arrangement ensures that the entire area enclosed by the diaphragm 10 and the casing 16 with the pipe 19 is sealed against the admission of atmospheric air.

A feed cable 280 for the excitation coil 15 extends within the pipe 19 and passes out hermetically through a bore 290 formed in a nipple 300 screwed into the side of pipe 19. A packing ring 310 is located between the nipple and the pipe 19. The outer end of the nipple is formed with a funnel-shaped seating surface 320 for a rubber sealing ring 330 which is pressed by means of a cap nut 340 against the seating surface and the cable 280 passing through it.

When the appliance is used for instance in hot water, the air enclosed in the casing is considerably heated externally by the water surrounding the casing and internally by the electrical losses of the driving system, the pressure above atmospheric so produced opens the non-return valve against the action of spring 250, thus compensating for the pressure difference in the casing relative to the atmosphere. Upon such compensation being effected, the valve is returned to its seat to seal the interior of the appliance against the admission of air from the atmosphere.

Whilst the appliance remains in operation, no pressure differences will occur between the interior of the casing and the atmosphere which may be sufficient to disturb the desired operation. However, as soon as the appliance is further operated in cold water or is taken out of the hot water, switched off, and placed in a cool place, it is possible, due to the airtight casing, for a pressure below atmospheric to occur in the interior of the casing which is sufficient to prevent the correct functioning of the diaphragm, at least until the appliance has been sufficiently heated again. It has, however, been found that a casing possessing the required airtight properties cannot be obtained by simple means, as, in the course of time, a pressure compensation or balance takes place either by way of the cable cores or the cable passage, or by way of the valve.

The example shown in Fig. 9 omits the non-return valve of Figs. 7 and 8 for solving the problem with which the invention is concerned, but other means is provided to ensure that the space enclosed by casing 16 and diaphragm 10 will conform to any alteration of the air pressure con-

tained therein, without the difference between the pressure in the casing and the atmosphere thereby assuming such proportions likely to interfere with the action of the appliance. For this purpose there are fitted, as for instance to the interior of the casing wall, resilient or yielding hollow bodies 400, which are formed in this example by bellow-like chambers 410 of thin sheet metal which are sealed from the interior of the casing by means of lids or covers 420, whilst the other end of the bellow-like chambers are soldered or welded to the casing wall. The casing wall has holes 430 which communicate with the interiors of the chambers.

In lieu of such sheet metal chambers, sack or bag-like bladders of rubber or similar materials may also be used as shown in Fig. 10 in which a hollow body 400a of this kind is provided with a small pipe piece 400b which passes through the opening 430 of the casing wall. The pipe piece has a flange 400c which is pressed against the casing wall by means of a cap ring 400d screwed to the casing.

On increase of air pressure within the casing, the bellows are compressed and thus the interior space in the casing is correspondingly enlarged. Thus the pressure above atmospheric is limited to an extent which will not affect the action of the vibration producer.

Fig. 11 illustrates a further example in which the electro-magnetic driving means 13 is hermetically enclosed in a pot-like casing 450, which is hermetically sealed by a cover plate 460. A central opening 470 is formed in the cover plate through which a bolt 480 extends from the interior of the casing. In the annular space between the bolt and the inner edge of the cover plate formed by the central opening 470 is disposed an elastic or resilient member such as a corrugated diaphragm or membrane 490 which is hermetically connected with the bolt and with the cover plate, for instance, by soldering. The flexible member is of sufficient dimensions to permit the required longitudinal movement of the bolt on operation of the driving means.

The laminated armature body 12 of the electromagnet 13 is secured to the internal end of the bolt, and a vibratory or oscillatory body in the form of the metal diaphragm 10 is secured to the external end. The diaphragm is secured at its outer edge to a ring 500 which is firmly connected with the casing 450 by spaced struts or extensions 510 which may be formed integral with casing 450.

In this example, the problem of the invention is solved by constructing the surface at which a pressure above atmospheric arising in the casing may engage on the moving parts of the driving means, as small as possible. The entire engaging surface for the pressure force is thus composed of a small part of the diaphragm surface 490 and the cross-section area of the bolt 480.

A further example of the subject of the invention is shown semi-diagrammatically in Fig. 12. In this case, the casing 520 enclosing the electromagnet 13 is made as small as the dimensions of the electro-magnet permit in order that the space enclosed by the casing and the diaphragm 10 may be as small as possible. As in the other examples, a pipe 19 is connected to the base of the casing for the passage of the electricity supply lead 280 to the electro-magnet 13 of the appliance. The free end of the pipe 19 is in effect widened to form a chamber 530 which is located

as remote as possible from casing 520 and is not immersed in the hot water during operation of the appliance. As shown, the capacity of the chamber 530 greatly exceeds that of the casing 520 in order to maintain a low gauge pressure occurring in the casing 520 on the heating of the air present therein. This is achieved, as previously mentioned, by the fact that the casing 520, which is immersed in hot water when the appliance is operated, has a much smaller air capacity than the chamber 530 which thus remains considerably cooler than the casing, the latter being situated outside the water container. When the air enclosed in the casing 520 expands owing to heating, it will mix with the cooler air in the pipe 19 and in the chamber 530 and the temperature rise relative to the atmospheric air, corresponding to the volume and temperature conditions of the two masses of air, will be considerably less than the temperature rise which would obtain in the air in the casing 520 if the chamber 530 were not present.

We claim:

1. In an electrical appliance for laundry purposes for producing vibrations in liquids, a vibratory body in the form of a diaphragm of stiff material such as metal, and electro-magnetic driving means for vibrating said body, said electro-magnetic means including a movable armature connected to said diaphragm, and a stop for limiting the movement of said armature.
2. In an electrical appliance for laundry purposes for producing vibrations in liquids, at least two vibratory bodies in the form of diaphragms, a single electro-magnetic driving device for actuating said diaphragms and at least one stop for abruptly limiting the movements of at least one of said diaphragms in at least one direction.
3. In an electrical appliance according to claim 2, in which one diaphragm is connected with the armature and the other with the core of the electro-magnetic driving device.
4. In an electrical appliance for laundry purposes for producing vibrations in liquids, a drum-shaped chamber, vibratory bodies in the form of diaphragms constituting opposed side walls of said chamber and thereby sealing the same, an electro-magnetic driving means in said chamber and located between said diaphragms for independent actuation thereof and at least one stop for abruptly limiting the movements of at least one of said diaphragms in at least one direction.
5. In an electrical appliance for laundry purposes for producing vibrations in liquids, a vibratory body in the form of a diaphragm, electro-magnetic driving means for vibrating said diaphragm, at least one stop for abruptly limiting the movements of said diaphragm in at least one direction, at least one additional vibratory body also driven by said driving means and having an independent frequency of vibration substantially above that of the diaphragm.
6. In an electrical appliance according to claim 5, an additional vibratory body in the form of a beam, said beam being rigidly connected with the diaphragm.
7. In an electrical appliance according to claim 5 an additional vibratory body in the form of a disc, said disc being rigidly connected to the diaphragm.
8. In an electrical appliance according to claim 5, an additional vibratory body in the form of a corrugated disc, said disc being rigidly connected to the diaphragm.
9. In an electrical appliance for producing

vibrations in liquids, a water-tight casing sealed against the admission of air, a diaphragm carried by said casing, electro-magnetic driving means enclosed in said casing for vibrating said diaphragm and means to relieve excess pressure in the casing arising from temperature changes and at least one stop for abruptly limiting the movements of said diaphragm in at least one direction.

10. In an electrical appliance according to claim 9, a pipe connected with the casing, a non-return valve disposed adjacent the end of the pipe, an electricity supply lead for the electro-magnetic means passing through the pipe and extending through the wall thereof in an air-tight manner.

11. In an electrical appliance according to claim 9, a diaphragm forming a part of the wall of the casing enclosing the electro-magnetic means and at least another part of the wall being more flexible than the diaphragm.

12. An electrical apparatus for laundry purposes for producing vibrations in liquids, a vibratory body, electro-magnetic driving means for vibrating said body, including an electro-magnet, an armature and a member connecting the armature with the vibratory body, a water-tight casing enclosing said electro-magnet and armature including a wall having an opening therein through which said connecting member passes and sealing means between said connecting member and said wall and at least one stop for abruptly limiting the movements of said diaphragm in at least one direction.

13. An electrical apparatus for laundry purposes for producing vibrations in liquids, a vibratory body, electro-magnetic driving means for vibrating said body, including an electro-magnet, an armature and a member connecting the armature with the vibratory body, a water-tight casing enclosing said electro-magnet and armature including a wall having an opening therein through which said connecting member passes and a small diaphragm between said connecting member and said wall serving to seal the opening in said wall and at least one stop for abruptly limiting the movements of said diaphragm in at least one direction.

14. In an electrical appliance according to claim 9, an additional chamber in communication with the casing enclosing the electro-magnetic driving means, said chamber being spaced apart from said casing so that it remains outside the washing liquid when the appliance is immersed therein during operation.

15. In an electrical appliance according to claim 9, an additional chamber in communication with the casing enclosing an electro-magnetic driving means, said chamber being spaced apart from said casing so that it remains outside the washing liquid when the appliance is immersed therein during operation, the air capacity of said additional chamber being at least twice that of the interior space of the casing enclosing the electro-magnetic driving means.

16. In an electrical appliance for producing vibrations in liquids, a diaphragm, electro-magnetic driving means for vibrating said diaphragm,

and at least one stop for abruptly limiting the movements of said diaphragm in at least one direction.

17. In an electrical appliance according to claim 16, an electro-magnetic driving means including a movable armature connected to said diaphragm and movable relative to the stop.

18. In an electrical appliance according to claim 16, an electro-magnetic driving means including an iron core which forms the stop for the diaphragm.

19. In an electrical appliance for producing vibrations in liquids, a diaphragm in the form of a circular disc, a cup shaped casing, said diaphragm being attached to the edge of the casing, an electro-magnet comprising a core fastened to the casing, a coil arranged on the core, and an armature rigidly connected to said diaphragm, the distance between the armature and the magnet core being so dimensioned that the movement of the diaphragm and core on their attraction by the electro-magnet is abruptly stopped by the core.

20. A portable electrical appliance for producing vibrations in liquids comprising a diaphragm, a concavo-convex casing having its concave side facing the diaphragm, said diaphragm being attached at its periphery to the edge of the casing, an electro-magnet comprising a core mounted on the concave side of the casing at the center thereof, a coil arranged on the core and an armature rigidly connected to the diaphragm and confronting the core, the distance between the armature and core being so dimensioned that the movement of the diaphragm on the attraction of the electro-magnet being abruptly limited by the core which defines a stop.

21. The combination of claim 20, wherein means is attached to the center of the convex side of the casing and extends laterally therefrom for holding the casing in a liquid bath.

22. In an electrical appliance for laundry purposes for producing vibrations in liquids, a vibratory body, electro-magnetic driving means for vibrating said body, and at least one stop for abruptly limiting the movements of said body in at least one direction, said electro-magnetic driving means including an iron core which forms the stop for said body.
